(57) **CLAIM**

The ornamental design for a headlamp bezel, as shown and described.

DESCRIPTION

FIG. 1 is a perspective view of a motor vehicle with a headlamp bezel according to our new design;

FIG. 2 is a perspective view of the headlamp bezel of FIG. 1;

FIG. 3 is a front view of the headlamp bezel of FIG. 1; and, FIG. 4 is a right side view of the headlamp bezel of FIG. 1. The broken line showing of a motor vehicle in FIG. 1 depicts environment and is not part of the claimed design. The portions shown in broken lines in FIG. 2 are for illustrative purposes only and forms no part of the claimed design.

The top, bottom, rear and left side of the headlamp bezel are unadorned.

The headlamp bezel shown in FIGS. 1-4 illustrate a first embodiment of our novel design suitable for use on the driver's side of a motor vehicle, such as a highway tractor. Our novel design also includes a second embodiment suitable for use on the passenger side of the vehicle, which is mirror symmetrical to FIGS. 1-4 and therefore not separately illustrated.
